[57] CLAIM

The ornamental design for an arcuate cutting tool, as shown and described.

DESCRIPTION

FIG. 1 is a side elevational view of an arcuate cutting tool embodying my invention;

FIG. 2 is a side elevational view of the same taken at ninety degrees to the right of that shown in FIG. 1;

FIG. 3 is a side elevational view taken at ninety degrees to the left of that shown in FIG. 1;

FIG. 4 is a side elevational view taken at one hundred and eighty degrees to that shown in FIG. 1;

FIG. 5 is a top plan view thereof;

FIG. 6 is a bottom plan view of the device in FIG. 1.
